[57] CLAIM

The ornamental design for a carriage for a child, as
shown and described.

DESCRIPTION

FIG. 1 is a front and side perspective view of a carriage
for a child showing my new design;

FIG. 2 is a front and side perspective view thereof,
showing the seat support frame in an alternative position;

FIG. 3 is a front elevational view thereof; and

FIG. 4 is a top plan view thereof.

FIG.1.

FIG. 2.

*FIG. 3**FIG. 4*
